Parker Cook.

Attorney

UNITED STATES PATENT OFFICE.

JOSEPH SIEGEL, OF DETROIT, MICHIGAN, ASSIGNOR TO AMERICAN LADY CORSET COMPANY, OF DETROIT, MICHIGAN, A CORPORATION OF MICHIGAN.

COMBINED STEP-IN AND BRASSIÈRE.

Application filed May 18, 1925. Serial No. 31,001.

To all whom it may concern:

Be it known that I, JOSEPH SIEGEL, a citizen of the United States, residing at Detroit, in the county of Wayne and State 5 of Michigan, have invented certain new and useful Improvements in Combined Step-Ins and Brassières, of which the following is a specification.

My invention relates to new and useful 10 improvements in women's undergarments and more particularly to a garment which is in the nature of a combined "step-in" and brassière.

One of the principal objects of the invention is to provide a garment of this 15 nature which will be extremely neat in appearance and conform to the style and desires of the present day.

Garments of this kind or a similar nature, 20 are selected and worn which tend to give a "straight-line figure" and it is therefore desirable to provide a garment which will tightly hug or fit the wearer above the waist and lie flat especially in the front and back 25 so that the outer clothes will be tight fitting and also give the desired flat appearance.

Still another object of the invention is to so construct the garment that while the brassière top or upper portion fits firmly 30 and the front panel presents the flat appearance, still the lower portion of the garment, which is in the form of a "step-in" is given a certain amount of flare.

Still another object of the invention is to 35 provide a very attractive garment which may be made of silk or other desired material, and consists of a front panel and rear panel, both of which extend the entire length 40 of the garment, two leg portions, attached respectively to the front and rear, and two upper portions attached to the front and rear panels and to the leg portions; thus providing a combination garment, functioning as a brassière and a "step-in". At 45 the same time, the garment is arranged to give the wearer the flat appearance and allow the "step-in" portion to flare at the side, thus insuring comfort to the wearer, and also simulating the appearance of a 50 short petticoat.

Still another object of the invention is to provide a garment of this nature wherein 55 the several parts may be made up or cut in large quantities and then neatly assembled at a relatively low cost to thereby provide

an economical garment from the standpoint of the manufacturer as well as a pleasing one for the trade or wearer.

With these and other objects in view, the invention consists in certain new and novel 60 arrangements and combination of parts as will be hereinafter more fully described and pointed out in the claims.

Referring now to the drawings,

Fig. 1 is a front elevation with the flare 65 of the lower portion slightly exaggerated to show the mechanical construction of the garment.

Fig. 2 is a similar view but taken from the rear, and

Fig. 3 is a sectional view taken on line 70 3—3 of Fig. 1.

Referring now to the several views showing a preferred embodiment of the invention, there will be noticed a panel 1, which extends the entire length of the garment, the panel tapering slightly at the waist line as at 2. A similar panel 3 is shown extending the entire length of the rear of the garment and this panel may be in two 75 80 pieces as shown in Fig. 2, the upper portion being reinforced as at 4 with braid, tape, or other suitable material, the fastening means 5 being attached to the reinforcements, which fastening means may be in the nature 85 of snaps, hooks and eyes, or other suitable fasteners.

In Fig. 2 the rear panel is shown with the center seams 6, but this panel might be made in one piece also, if desired, and then 90 cut at its upper portion so that the garment may be opened and closed when necessary.

These front and rear panels are preferably made of silk; in fact, the entire garment is preferably made of silk, although cheaper 95 grades may be made in cotton or other desired material.

The upper portion of the garment, or what I call the brassière top, consists of the two portions 7 and 8 which are folded 100 as may be seen in the several figures and the edges of these two portions respectively sewed to the front and rear panels 1 and 3, thus providing the seams 9 and 10 in the front of the garment 11 and 12 at the rear 105 thereof.

The lower part of the garment, or the "step-in" portion also consists of the two leg portions 13 and 14, the upper ends of these 110 respective portions being sewed to the lower

end of the brassière portions 7 and 8, the 5
seams 15 and 16 thus occurring at the waist
line 2. These leg portions are folded similar
to the top portion and are stitched also to the
front and rear panels as may be seen by the
seams 15 and 16 at the front, and 17 and 18,
at the rear. The tab 19 is sewed or stitched
as at 20 to the rear panel.

The two pieces 13 and 14 of the "step-in" 10
portions are cut on a taper so that the bot-
tom portion thereof is wider than the upper
portion and when the garment is worn and
the brassière portion is fastened about the
bust, there will be a tendency for the "step-
in" portion to flare as shown in the several
figures.

If the garment were held in the hand or
suspended as shown in the drawing, of
course the skirt or lower portion would tend
20 to hang nearly parallel with the sides of
the brassière or top portion, and in the
drawing, the flare is exaggerated to show
how the garment is mechanically cut and
assembled.

25 Straps 21 are shown at the upper edge of
the brassière portion and a lace band 22 is
shown at the top of the garment, while the
lower edges of the "step-in" may be also
ornamented with lace as shown at 23, to
30 beautify the garment.

By slightly tapering the panels at the
waist line, and by tapering the several por-
tions of the leg part of the garment, and by
35 forming the seam at the waist line, the gar-
ment, when worn, will snugly fit the wearer
at the upper part of the body holding the
bust while the lower portion will tend to
flare, thus providing comfort and giving the
40 pleasing effect desired.

45 Furthermore, the garment being built
about the two parallel panels, which extend
the entire length of the garment, will give
the wearer the straight line or flat effect in
the front, which is the so much desired ap-
pearance at the present time.

50 From the foregoing it will be seen that
the one garment serves the purpose of two
separate garments, is easily and economical-
ly made and provides an article of clothing
55 which is very neat in appearance, may be
easily and quickly changed and also pro-
vides the comfort incident to a garment of
the "step-in" type.

I am aware that it is old to provide a
55 garment being close fitting about the waist
and loose about the lower part of the body
and I do not broadly claim my invention
as such, but what I do claim and desire to
secure by Letters Patent is:—

1. A combination "step-in" and brassière 60
comprising a front and rear panel, both of these panels tapering slightly to
the waist line and then presenting straight
line edges throughout their length, the
brassière portion comprising two folded 65
pieces having their edges secured respec-
tively to the front and rear panels, and the
lower portion of the garment comprising
two pieces of material which are folded and
also have their edges respectively secured 70
to the front and rear panels, these lower
pieces tapering at the waist where they
are attached to the brassière top, and the
"step-in" portion adapted to flare at its
75 sides, the rear panel being divided in its
upper portion and fastening means being
secured to the adjacent edges of the divid-
ed portion.

2. A woman's undergarment comprising 80
a similar front and rear panel extending
the length of the garment, two pieces of
material each of which is folded and se-
cured to the sides of the upper portion of
the front and rear panel, two leg pieces 85
each of which is cut on a taper and folded,
the straight edges being secured to the
edges of the front and rear panels respec-
tively, the upper edge of these pieces join-
ing at the waist line with the top portion,
the rear panel being divided and fastening 90
means being secured thereto, the front and
rear panels being secured at their lower
edge to form separate leg portions, the ar-
rangement of the different panels and pieces
and the location of the seams being such 95
that the garment will lie flat in front and
flare at the sides in the lower portion.

3. A combination brassière and "step-in" 100
consisting of a similar front and rear panel
extending the length of the garment and the
rear panel divided and fastening means
secured thereto, the front and rear panels
secured at their lower ends and two leg por-
tions cut on a taper folded and respectively 105
joined to the side edges of the front and
rear panels, a brassière top having its lower
edges secured to the top of the leg portions
to form the seam at the waist line, and
the pieces of the brassière portion also se-
cured to the edges of the front and rear 110
panel, and this top portion adapted to
snugly fit the wearer, and the lower por-
tion of the garment adapted to snugly fit
the wearer at the front and back, and flare
at the sides.

115 In testimony whereof I affix my signature.

JOSEPH SIEGEL.
